INVENTOR

UNITED STATES PATENT OFFICE

96,088

DESIGN FOR A TEXTILE FABRIC

Malcolm Brown, New York, N. Y.

Application May 25, 1935, Serial No. 57,014

Term of patent 3½ years

To all whom it may concern:

Be it known that I, Malcolm Brown, a citizen of the United States of America, residing in Manhattan, county of New York, and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

I claim:

The ornamental design for a textile fabric, substantially as shown.

MALCOLM BROWN.
